UNITED STATES PATENT OFFICE

NOBLE H. WATTS, OF OAKLAND, CALIFORNIA, ASSIGNOR, BY MESNE ASSIGNMENTS, TO
GENERAL ELECTRIC COMPANY, OF SCHENECTADY, NEW YORK, A CORPORATION OF
NEW YORK

ATTACHMENT PLUG CAP

Application filed June 7, 1926. Serial No. 114,300.

This invention relates generally to a connection terminal for electrical cords.

It is an object of this invention to devise a connection terminal for a cord which will be practically indestructible.

It is a further object of this invention to devise a connection terminal which will be sealed against external vapors and liquids.

It is another object of this invention to devise a novel connection terminal which will incorporate a resilient insulating material such as rubber.

It is a further object of the invention to devise a cord terminal which will have no exposed screws or bare wires and which will not become short circuited.

The further objects of the invention will appear from the following description in which I have set forth the preferred embodiment of my invention. It is to be understood that the appended claims are to be accorded a range of equivalents consistent with the state of the prior art.

My invention is illustrated in the accompanying drawing forming a part of this application, in which—

Figure 1 is a longitudinal section through the device.

Figure 2 is a section along the line 2—2 of Figure 1.

Figure 3 is a front elevation of the device, and

Figures 4 and 5 are views similar to Figure 3, but showing the terminals of the cap in different positions.

In carrying out my invention I provide a cable 1, which houses two insulated wires 3 and 4. Terminals 5 and 6 of the shape shown in Figure 2, are carried by an insulating housing 7, and are connected to the wires 3 and 4 in a manner now to be described.

Each terminal has an eyelet 8 around which the insulated wire is wrapped one or two revolutions. The bare wire is then wrapped an additional number of turns around the portion of the terminal forming the eyelet, and is then soldered to the terminal. I have found that the portion of the wire disposed adjacent to the soldered

point will not flex so readily, and it is for this reason that I have provided a number of turns of wire to permit relative movement of the terminal with respect to the wire, without the wire becoming broken through use.

After the wires 3 and 4 have been wrapped around their respective terminals 5 and 6 in the manner just set forth, a core 9 is forced through the eyelet 8 and spaces the terminals 5 and 6 the required distance apart. The casing 7 is now set into place and is vulcanized to the core 9. It will therefore appear that the terminals 5 and 6 are completely surrounded by rubber. The casing 7 has a sleeve 10 which encloses the cable 1 for a slight distance.

From the foregoing description of the various parts of the device, the operation thereof may be readily understood.

I have shown a plug 11 in dotted lines in Figure 1, as being attached to the cap 7. If the terminal receiving openings in the plug 11 should be a greater distance apart than the distance between the terminals 5 and 6, the casing 7 could be depressed in the manner shown in Figure 3, whereupon the terminals 5 and 6 would be moved the required distance apart, thus permitting the cap to be inserted in the plug. The cap 7 would be depressed in the manner shown in Figure 5 in case the openings in the plug 11 were close together.

The casing 7 is made of rubber and provides a casing which performs a threefold function, in that the casing insulates the terminals 5 and 6 from each other, it permits the terminals to be moved toward or away from each other, and it also yieldingly holds the terminals together, thus exerting a sufficient force for causing the cap 7 to be secured to the plug 11.

I claim:

1. A device of the type described, comprising a cable carrying wires, terminals having eyelets at one end thereof, said wires being wrapped around said eyelets, an insulating and resilient core passed through said eyelets, and an insulating and resilient casing 95
- 100

securing said core and said terminals to said cable.

2. In a resilient terminal, a resilient body of insulating material, a pair of spaced contact strips having their ends embedded in the resilient material of the body whereby the exposed ends of the contact strips may give relative to each other due to the resilient nature of the body, and a single anchoring member embedded in said body and connected to the embedded ends of both strips.

10 In testimony whereof I affix my signature.
NOBLE H. WATTS.
